DIRECTION INDICATOR

Robert Shaw Miller, Ashton-under-Lyne,
EnglandApplication August 3, 1934, Serial No. 738,331
In Great Britain July 8, 1933

8 Claims. (Cl. 177—329)

This invention relates to direction indicators for motor and like vehicles and to traffic control signalling devices, and has for its object to provide improved indicators and means for operating the same which shall be very effective in service.

The invention relates more particularly to a direction indicator or traffic control signalling device of the type in which a casing with its axis vertical has a pointer projecting radially therefrom, the casing being turned about its axis by electrical means to give the desired signals or direction indications.

The invention comprises the arrangement wherein electromagnetic means on energization cause axial movement of the casing relatively to the stationary portion of the indicator, the casing during and as a consequence of such axial movement being caused to turn about its axis.

The invention further comprises the arrangement wherein the casing is secured to and moves with a member or members constituting a movable armature for an electromagnet which forms part of the said stationary portion of the indicator, spring means being provided normally to maintain the casing with the pointer in the normal or "no turn" position, and the armature clear of the electromagnet, the spring pressure being overcome by the attraction between the electromagnet and its armature when the former is energized.

The invention further comprises the arrangement wherein the pointer comprises a glass tubular member secured to the casing of the device and illuminated by an electric lamp within the casing.

The invention further comprises the arrangement wherein the pointer is constructed as a framework of metal strip-like elements which carry an electric lamp between them towards the outer end of the pointer, the strip like elements being held together at their outer ends by a nut threading on to screw threaded parts on the strip-like elements.

The invention further comprises the details of construction hereinafter described and claimed.

Referring to the accompanying drawing:—

Figure 1 is a part sectional side elevation of a direction indicator for motor and like vehicles constructed in one convenient form in accordance with the invention, with the parts in the positions they occupy when the device is indicating that a turn is to be made.

Figure 2 is a sectional plan view on the line 2—2 of Figure 1.

Figure 3 is a sectional plan view on the line 3—3 of Figure 1.

Figure 4 is a part sectional end elevation on the line 4—4 of Figure 1 looking from right to left.

Figure 5 is a view similar to Figure 1 of a modified construction of indicator, but with the parts in the positions they occupy for ahead driving.

Figures 6 and 7 are a plan view and a part sectional end elevation on the line 1—1, of Figure 5 respectively, showing the mounting of the electric lamp within the pointer.

Referring to Figures 1 to 4, the indicator comprises a casing *a*, which may be of moulded insulating material, with a pointer *b* and tail fin *c* secured thereto so as to project radially from opposite sides as shown. The pointer *b* is constituted by a fluted conical glass tubular element *b*² bounded above and below by a frame *b*¹ of V section strip metal. The outer end *b*³ of the glass element is solid and the inner flanged end is held in a recess in the casing *a* by brackets *b*⁴ upon the frame *b*¹ which are attached to the casing by screws *d*. The strip metal members of the frame *b*¹ are squeezed at their outer ends, as shown in Figure 2, to hold between them a suitably coloured strip *e* preferably of red celluloid. Rivets *e*² hold the strip *e* against displacement. A further strip *e*¹ passes axially through the tubular element *b*². The solid end *b*³ of the latter is provided with external grooves to receive the coloured strip *e* which then serves to steady the end of the tubular element *b*². The tail fin *c* is attached to the casing by screws *d*.

The stationary part of the indicator comprises a central tubular member *f* having an electromagnet *g* with pole piece *h* mounted thereupon. Secured to the lower cylindrical part of the casing *a* by a cap *i* is a cylindrical member *j* which is a sliding fit upon the tube *f* and constitutes the armature of the electromagnet *g*. The electromagnet is energized by current from a lead *k* (passing through the bore of the tubular member *f*) under the control of a switch mounted in any suitable position for convenient operation by the driver of the vehicle. A spring *m* is interposed between the cap *i* and the casing of the electromagnet *g* normally to hold the armature away from the pole piece *h*, the resistance of the spring being overcome when the electromagnet is energized, the parts then assuming the position shown in Figure 1.

Secured to the top of the casing of the electromagnet *g* by long screws *n* is a lens carrier *o* having the lenses *p* secured therein in any suit-

able manner. As shown in the drawing there are four lenses, the two in line with the pointer and tail fin being red and those at right angles thereto being green for a purpose to be herein-
5 after referred to. A festoon type double ended electric lamp *q* is carried axially in the lens carrier in a holder constituted by spring strips *r*, *r*¹. Current is supplied to the lamp *q* from the lead *k* by contacts *s* on the lamp holder strips *r*, *r*¹.

10 Non-rotatably mounted in the upper part of the lens carrier *o* and disposed axially of the indicator is a helically grooved stud *t* which co-operates with a nut of particular construction which may be moulded in the casing *a*. The
15 nut consists of four steel balls *u* carried between a pair of apertured square cheekpieces *v* held together by a short square tubular element *w*. The balls are self-locating, taking up the positions shown in Figure 3 when the nut is threaded on to 20 the stud *t*. A screw plug *x* closes the upper part of the casing *a*. If desired the casing itself may form the cap which in the illustration is provided by the plug *x*.

With the construction of indicator described,
25 two of such indicators may be used for each vehicle, one for giving right hand indications and the other for giving left hand indications. The indicators may be mounted upon brackets upon side pillars of the vehicle, upon the side lamps
30 or in any position where they give the necessary indications to other traffic and to those who control traffic. A single switch of any suitable form may be mounted upon the facia board or steering column of the vehicle to control the indications given by both indicators, the respective lamp and magnet circuits being arranged in parallel.

35 The operation of the device is as follows:—

To give a signal that the vehicle is going to make a turn, the switch is operated to complete 40 the lamp and magnet circuits of the appropriate indicator. The energizing of the magnet *g* causes attraction of the armature *j*, the latter moving upwardly, causing axially upward movement of the casing *a*. The latter however, by 45 reason of the fact that its connection with the stationary part of the indicator is constituted by the helically grooved stud *t* and nut *w*, also makes a turning movement the pitch of the helical groove on the stud *t* is such that for the amount of axial movement of the casing *a*, the latter turns through 90°. The pointer *b* is 50 turned into the position shown in Figure 1 and a brilliant red illumination of the pointer *b* and tail fin *c* will be produced by light passing from the lamp *q* through the red lenses *p*. In the case of the pointer, the light from the respective lens passes along the glass tubular element *b*² and the red illumination of the pointer is enhanced by the strip *e*, *e*¹. It will be noticed that 55 the pointer *b* comes opposite the lenses *p* by reason of its axial and rotative movement and is normally axially displaced from the lenses by the amount of axial movement of the casing. When the switch is operated to break the lamp and magnet circuits, the spring *m* forces the 60 armature *j* and cap *i* downwardly, and the casing *a* and pointer *b* move helically downwards until the pointer *b* projects in the direction of travel of the vehicle. To give a signal that the vehicle 65 is going to proceed straight ahead, the switch is operated to complete the lamp circuit only, when a green light will show forward by light passing from the lamp through one of the green lenses and along the pointer. It will be appreciated
70 from Figure 2 that the thickness of the strip *e*,
75

*e*¹ and of the framework *b*¹ is insufficient to form any appreciable obstruction to the passage of such green light.

75 The connection between the casing *a* and the stationary part of the indicator is the equivalent of a quick pitch screw thread.

It will be appreciated that a right hand indicator has a helical groove, slot or screw thread of opposite hand from an otherwise similarly constructed left hand indicator so that the electromagnetic attractive effort produces in the former case axial movement, and angular movement to the right of the casing, and in the second case axial movement and angular movement to the left of the casing.

10 Referring to Figures 5 to 7, in the modified construction of indicator shown therein, the central source of illumination and lens carrier are dispensed with and the pointer is illuminated externally by a lamp *q* at the outer end of the 20 pointer. The latter is constituted by a pair of V section strip metal elements *y* of the shape shown, attached to the casing *a* as before and a second pair of strip metal elements *z* which together with the elements *y* form a holder for the lamp *q*. The 25 outer ends of the strip metal elements *y* and *z* are brought together and held by a cap *f* which threads or clips thereonto. The arrangement of the electromagnet and its armature is the same as in the embodiment already described, but the helically grooved stud *t* is carried directly by the 30 casing of the electromagnet. Current is supplied to the lamp through the strip metal elements *y*, from the lead which passes through the tubular member *f* already described. The lamp *q* may be provided with a rod or other suitably coloured screen therearound. The operation of the indicator will be evident from the description of the 35 operation of the indicator shown in Figures 1 to 4.

40 The device may be employed for traffic control signalling, for example to indicate when vehicles are to be allowed to turn to the left against a traffic light signal, or a series of devices may be employed to direct incoming traffic into vacant 45 parking spaces.

What I claim is:—

1. A direction indicator of the type described comprising a support, a rotatable casing external to and mounted on said support, an indicator mounted directly upon said casing, electro-magnetic means in said casing adapted to impart axial movement to said casing and means to constrain said casing to rotate during said axial movement.

50 2. A direction indicator of the type described comprising a rotatable casing, a support for said casing, an indicator on said casing, electro-magnetic means adapted to move said casing axially and mechanical means removed and separate from said electro-magnetic means adapted to be operated by said casing during its axial movement to impart a rotary movement to said casing.

55 3. A direction indicator as claimed in claim 1 wherein the said casing is secured to and moves with a member constituting a movable armature for an electromagnet and in which there are spring means adapted to resist movement of said armature by said electromagnet and to restore said armature to its rest position upon cessation 60 of action of said electromagnet.

65 4. A direction indicator as claimed in claim 2 wherein the said casing is secured to and moves with a member constituting the movable armature electro-magnetic means and in which there are

spring means adapted to resist movement of said armature by said electromagnet and to restore said armature to its rest position upon cessation of action of said electromagnet.

5 5. A direction indicator according to claim 1 wherein the means specified which constrain said casing to rotate during its axial movement comprise a quick screw thread connection between the casing and a stationary portion of the indicator.

10 6. A direction indicator according to claim 1 wherein the means specified which constrain said casing to rotate during its axial movement comprise a helically grooved stud mounted upon said support of the indicator and a co-operating nut 10
15 non-rotatably mounted upon the said casing.

7. A direction indicator according to claim 1 wherein the means specified which constrain

said casing to rotate during its axial movement comprise a helically grooved stud mounted upon said support of the indicator and a co-operating nut non-rotatably mounted upon the said casing, the said nut comprising four balls located in the corners of a frame member in the form of a hollow square. 5

8. A direction indicator according to claim 2 wherein the mechanical means specified comprise a helically grooved stud and a nut co-operating therewith, said nut comprising a square hollow frame member within the four corners of which four balls are located, said nut and said stud being non-rotatably mounted one upon said casing and one upon said support of the indicator. 10
